U.S. PATENT DOCUMENTS

2,815,556 A 12/1957 Neil
4,143,498 A 3/1979 Martin, Jr.

FIG. 1 is a front, top, right side perspective view of a wire cover end cap with wire passage showing my new design;

FIG. 2 is a top plan view thereof;
FIG. 3 is a front elevation view thereof;
FIG. 4 is a right side elevation view thereof;
FIG. 5 is a left side elevation view thereof;
FIG. 6 is a rear elevation view thereof; and,
FIG. 7 is a bottom plan view thereof.

The broken lines in the drawings are for the purpose of illustrating portions of the wire cover end cap with wire passage that form no part of the claimed design.
